UNITED STATES PATENT OFFICE.

GEORGE W. BROOKS, OF TOPEKA, KANSAS.

SCREED HOLDER.

Application filed December 10, 1923. Serial No. 679,583.

This invention relates to screed holders for concrete floors and the like, and more especially to such devices for application to concrete before it hardens and adapted after such event, to be adjusted to receive screeds for nailing strips and form anchors therefor.

My object in this connection, is to provide a screed holder of simpler and cheaper construction than any heretofore made, but which will possess in full measure, all the qualifications essential for efficient service.

With this general object in view, the invention consists in certain novel and useful features of construction and organization of parts as hereinafter described and claimed; and in order that it may be readily understood, reference is to be had to the accompanying drawing, in which:

20 Figure 1 is a perspective view of a section of concrete flooring and of a series of screed holders and a section of a screed in anchored relation to one holder and in alignment with the others.

25 Figure 2 is an enlarged vertical section on the line II—II of Figure 1.

Figure 3 is a perspective view of one of the holders as completed and ready for application to a soft concrete floor.

30 Figure 4 is a perspective view of a holder with the nailing or arm projecting outwardly in opposite directions and the body portion braced at the junction therewith of said arms.

35 Figure 5 is a section on the line V—V of Figure 4.

Figure 6 is a detail perspective view of the brace of Figures 4 and 5.

Figure 7 is a perspective view of a holder 40 having resistance or bracing parts at the junction of the arms and body, of modified form as regards the brace of the preceding construction.

Figure 8 is a perspective view of a screed 45 holder of flat or sheet metal, but provided with resistance or bracing features corresponding in mechanical function to those of Figures 4 and 7.

Figure 9 is a perspective view of a holder 50 of the same type as the preceding figures, but adapted to receive and anchor a wider screed.

Figure 10 is a side elevation of a modified 55 form of the screed disclosed by Figures 9 and 10.

Referring now to the drawing in detail,

it will be noted that Figures 1 to 7 inclusive, disclose holders made of wire as contrasted with the sheet metal holders of the remaining figures, but that in all cases the body portion 1 is of V-shape or double V-shape where screeds of considerable or unusual width are to be used. In all cases however, the extremities of the body portion terminate in arms adapted to occupy a horizontal 60 position until the screeds are to be secured in place.

In the simplest form of the invention as exemplified by Figures 1 to 3 inclusive, the arms 2 extend inwardly from the respective 70 ends of the body portion, and lie horizontally in overlapped relation, and in all of the wire-type forms, the said arms terminate in nailing eyes or loops 3.

In Figures 4 and 5, the arms extend horizontally outward from the respective ends of the body, and a brace 4 extends between said ends to brace the body at the junction with the arms. The brace is produced from a strip of flat metal longitudinally split at 75 its ends and folded in line with the splits to inverted V-form in cross section. The split ends are each bowed as at 5 to provide downwardly-converging loops and parallel end extremities 6. To apply the brace 80 the extremities are spread apart to permit the brace to be slipped down until arrested by the upper or end portions of the body. The extremities are then pressed together 85 so as to underlie the arms 2 and thus close 90 the loops snugly upon the body. The brace thus positioned constitutes an abutment for preventing movement or distortion of the body when the arms are bent upward preliminary to the reception of the screed. 95

In Figure 7, the material is bent to provide transverse portions or resistance abutments 7, joining the body portion and arms, so that the latter can be bent upward without distortion of the body portion, as described with respect to brace 4. 100

In Figures 8 and 9, the sides of the body are flanged or channelled, as at 8, to not only more effectually resist lateral movement of the body when the arms 2 are bent to upright position, but to stiffen the body so that its sides shall offer resistance at the bending points against distortion of the body during such bending operation. 105

The arms in said figures and in Figure 110 10, are provided with nail holes 9, for receiving the nails 10 used to secure the screed.

to and between the arms, the loops 3 being the equivalent in the wire constructions of said holes.

In Figure 10, the strip of metal of the body is preferably of heavier gauge than in Figures 8 and 9, and the sides are disposed in edgewise relation, the metal at the apex of the body being distorted laterally at 11 in substantially the same manner shown at 10 the apex of the body portion of Figure 8. The sides of the body portion at the junction with the arms 2, are twisted at 12, to permit the arms to lie in overlapping relation as shown, until ready for the reception 15 of the screed.

In all cases the holders are forced down into the concrete (as shown at the left-hand end of Figure 1), after it has set sufficiently to permit workmen to walk upon planks laid 20 upon it, the holders being arranged in as many parallel lines as there are screeds to be used.

The planks are then removed and after the concrete has hardened, workmen can 25 walk upon it or run wheel barrows over it without interference by the holders, as the arms of the latter lie flatly upon the surface of the concrete.

When ready to lay a floor upon the concrete, the arms 2 are bent upward as indicated in Figure 1 and by dotted lines in other figures, and the screeds S are placed upon the floor between such arms as shown by Figure 1, and are secured in position by 30 nails driven through the loops 3 or holes 9, as the case may be. The flooring, not shown, can then be nailed to the screeds.

From the above description it will be apparent that I have produced a device of the 40 character described which possesses all the features of advantage set forth as desira-

ble; and while I have described and claimed the preferred embodiment of the same, I reserve the right to make all changes properly falling within the spirit and scope of 45 the appended claims.

I claim:

1. A metal screed holder bent to form a body portion to be thrust into plastic concrete, and terminating in normally horizontal arms integrally formed with the body portion, said arms being provided with openings, and adapted to be bent at their junction with the body, to substantially vertical positions; the holder having means constituting resistance points at the junction of the arms with the body, to permit the arms to be bent without distortion of the body portion. 55

2. A metal screed holder of skeleton form 60 bent to form a depending body having downwardly-converging sides and normally horizontal arms at the upper ends of the sides and integrally formed therewith and provided with nail-receiving openings. 65

3. A metal screed holder of skeleton form bent to form a depending body having downwardly-converging sides and normally horizontal arms at the upper ends of the sides and integrally formed therewith, the 70 arms projecting in opposite directions from the respective sides of the body and having nail-receiving holes.

4. A metal screed holder bent to relatively W-shape to provide a driving point 75 for use in inserting the screed in the concrete, and normally horizontal arms at the opposite ends of said W-shape extending in opposite directions.

In witness whereof I hereunto affix my 80 signature.

GEORGE W. BROOKS.
